DRAFT REGULATOR FOR LOCOMOTIVES

Oswald Huwyler, Vienna, Austria

Application January 16, 1933, Serial No. 652,092
In Switzerland October 29, 1931

3 Claims. (Cl. 110—147)

This invention relates to improvements in draft regulator for locomotives for controlling the introduction of steam and of overgrate air for smoke-consuming devices, more particularly for use on locomotives. The hitherto known steam and overgrate air control gear types, such as are used more particularly on locomotives, and which are provided with an auxiliary blower valve and with a steam control valve, suffer from the drawback that the auxiliary blower works too powerfully when the smoke-consuming device is started up, with the result that in the first place too large a volume of air is supplied for the supporting of combustion, and in the second place the steam pressure rises too far and too rapidly, so that the smoke-consuming device has to be cut off again.

In order to overcome this objection to the known types of control gear for the described purpose in accordance with the present invention there are provided in the auxiliary blower valve both a channel which permits of the passage of a small quantity of steam, and which is automatically opened by the closing of the hand-controlled main steam valve and closed by the opening of the main steam valve, and also a second channel which permits of the passage of a larger quantity of steam than the previously-mentioned channel, but which is independent of the position of the main steam valve and controlled solely by the steam control valve.

This steam control valve is so linked up with the fire door that, on the opening of the fire door, it is automatically brought into such a position that it opens up the steam passage to the channel in the auxiliary blower valve which permits of the passage of only a small quantity of steam, while keeping closed the channel of larger cross-section, this latter channel is capable of being opened only by actuation of the steam control valve by hand.

The result achieved by the described arrangement is that, when the smoke-consuming device is started up, the auxiliary blower in the smoke box is set to work at a fraction of its capacity, which fraction however is sufficient to effect complete combustion of the smoke, while at the same time the possibility is provided of feeding the auxiliary blower for any desired working strength for the purpose of powerfully and rapidly forcing the fire to obtain rapid formation of steam. At the same time, account is taken of the requirement that, for the obtaining of complete combustion of smoke, when the

fire door is opened for the purpose of stoking (the main valve being of course closed), the auxiliary blower should in any event be set to work. This result is obtained, as already mentioned, by arranging for the auxiliary blower to be started up with a slight quantity of steam by positively-acting means when the fire door is opened. On the other hand, in the arrangement according to the present invention the feeding of the auxiliary blower with large quantities of steam is not automatically governed, in contradistinction to the known arrangements for the same purpose, but is hand-controlled, since an automatically acting device cannot adequately well adapt itself to the frequent and varying alterations in the demands made on the fire and in the time required for driving the gaseous content out of the fuel, or at least not if the device is to possess the simplicity necessary to make it eligible for surface under actual working conditions.

One form of construction embodying the principle of the invention is illustrated, by way of example, in the accompanying drawings, in which:

Fig. 1 is a front elevation of the fire door of a locomotive engine together with the steam and overgrate air control gear.

Fig. 2 shows in section the fire door and the overgrate air admission flap.

Fig. 3 is a vertical section of the steam control valve.

Figs. 4 and 5 are sections on the line A—B of Fig. 3, showing the shutting-off member in different operative positions.

Fig. 6 is a fragmentary top plan view of the fire door illustrating the device associated therewith for actuating the steam control valve.

Fig. 7 is a diagrammatic view in section of a locomotive showing the invention connected therewith.

Referring to Figs. 1 and 2 of the drawings, the fire door frame 1 is closed by the fire door 2 into which the overgrate air admission flap 3 is built. Into the combustion chamber there is arranged to project the steam jet nozzle 5 which is connected to a steam pipe 4, and which is supplied with steam from the pipe line 20 connected to the boiler, through a further pipe 24' and the steam control valve 6. The steam control valve 6 is connected by means of two pipes 21' and 22' to the auxiliary blower valve 7 from which a pipe 23' leads to the auxiliary blower 60 placed in the smoke box 61 shown in Fig. 7. Further, from the steam control valve 6 a pipe 27

leads to a steam cylinder 8 which actuates the overgrate air flap 3 in a manner to be described in due course. The steam control valve 6 has, as its controlling member proper (see Figs. 3 to 5), 5 a slide valve 32 which is adapted to be rotated by means of a lever 16 shown in Fig. 1. If this lever 16 be in position I the slide valve 32 assumes the position shown in Fig. 7 in which both the pipe 24' leading to the steam jet nozzle 5 10 and also the two pipes 21' and 22' leading to the auxiliary blower valve are closed off.

If the lever 16 be then brought into position II, which can be effected either by hand or automatically, 15 in a manner to be described later, in dependence on the opening of the fire door, the slide valve 32 assumes the position shown in Fig. 4 in which it uncovers both the channel 24 leading to the pipe 24' and to the steam jet nozzle 5 and also the pipe 21' to the auxiliary blower valve 7, while 20 still retaining the pipe 22' closed off. The pipe 21' leads to a channel 21 in the auxiliary blower valve 7 (Fig. 7), which channel has a passage for the steam of small cross-sectional area controlled by an adjustable throttling screw 35. In 25 the auxiliary blower valve there is further provided a hollow slide valve 36 with apertures 37, which slide valve can be displaced by means of a piston 28 which is made to respond to the movement of the main steam valve 62 through 30 the provision of the connecting pipe line 25 connecting the steam chest 64 with the auxiliary blower valve 7. As is well known in the art, the steam chest 64 is connected with the steam dome 35 65 of the locomotive by means of the pipe 66 controlled by the steam valve 62 provided with the adjusting handle 63. When the valve 62 is closed by means of the handle 63, so that no steam pressure is present under the piston 28 this piston and the hollow slide valve 36 occupy 40 under the action of the pressure of the steam entering through the pipe 21' the position in which they are shown in the drawings so that the steam flowing into the channel 21 can flow through the apertures 37 in the hollow slide valve 45 into the channel 23 and thence through the pipe 23' to the auxiliary blower 60. The auxiliary blower is thus supplied with a small quantity of steam, so that it works with just sufficient output to ensure complete combustion of the smoke. 50 If the valve 62 be opened steam flows from the steam chest through the pipe 25 under the piston 28, thus lifting the latter and pressing the hollow slide valve 36 upwards. The connection 55 between the channels 21 and 23 in the auxiliary blower valve is thus interrupted and the steam supply to the auxiliary blower thereby cut off. The space above the piston 28 is connected by means of the passage 26 with the atmosphere.

For the purpose of setting the auxiliary blower 60 for a powerful forcing of the fire the lever 16 is brought into position III, so that the slide valve 32 assumes the position shown in Fig. 5 in which it opens the pipe 22' leading to the 65 channel 22, 23 in the auxiliary blower valve, while at the same time the communication to the steam jet nozzle and to the channel 21 remains open. A considerable quantity of steam is thus allowed to pass through the channel 22, 23 to the auxiliary blower 60, and that irrespective of the position of the hollow slide valve 36, that is to say of whether the valve 62 be open or closed, because with open valve 62 the steam which enters the channel 22, is allowed to flow around the reduced shank portion of the slide valve 36.

The movement of the lever 16 from position II to position III and back from III to I is in any case effected by hand. The shifting of the same from position I into position II is, however, also effected in one particular case automatically, 5 namely when the fire door is opened with the lever 16 in any position between I and II. In this case the lever 16 is taken on into position II by the action of opening the fire door, so that every time the fire door is opened the slide valve 10 32 assumes the position shown in Fig. 4, provided this slide valve has not been moved already by hand into a still further open position.

For the transmission of the movement of the fire door to the lever 16 the following arrangement is adopted. On the fire door there is provided an engaging piece 13^a which co-operates with eccentric or crank members 13 and 14 which in their turn are connected to a tension rod 15 adapted to actuate the lever 16. The opening of 15 the fire door causes the engaging piece 13^a to engage and turn the crank members 13 and 14, and the tension rod 15 is thus drawn towards the right, so that the lever 16 connected to this tension rod is moved from position I to position II. 25

There is connected to the steam control valve 6, by means of a pipe line 27, a steam cylinder 8 which actuates the overgrate air flap 3. At the upper end of this cylinder 8 a connection to the atmosphere is provided by means of the passage 38 and the pipe 38'. When the lever 16 is moved from the position I into either of the positions II and III the cylinder 8 is also supplied with steam, with the result, that the piston 42 fitted 35 in this cylinder is lifted, together with the piston rod 17, against the action of a spring 44. The end of the piston rod 17 engages a bell-crank lever 18 which is thereby rotated and actuates a lever 19 attached to the axle of the overgrate air flap 3, so that this latter is opened. When the 40 door is opened, the lever 19 moves out of engagement with the lever 18, thereby permitting the flap 3 to close upon opening of the door.

In order to adapt the extent of the opening of 45 the overgrate air flap to the working requirements obtaining at any one time the piston rod 17 is adapted to be variable as to its length, the arrangement being such that one of a number of end pieces A, B, C of different length can 50 be fitted on the end of this piston rod. The longer the end piece used the wider the overgrate air flap will be opened at a certain steam pressure. The shortest of the end pieces A, B, C with which smokeless combustion can still be 55 obtained will always be selected for employment on the end of the piston rod 17. In this connection it should also be noted that the setting of the screw 35 (Fig. 7) in the auxiliary blower valve will also be governed by the principle of 60 keeping the auxiliary blower action down to the minimum which still ensures smokeless combustion.

In the above description only the three positions I, II and III of the lever 16 and of the slide valve 32 have been considered. It will however be clear that the lever 16 can have as many intermediate positions as desired. The three positions I, II and III merely represent the three 70 most characteristic positions, in position I the apparatus being out of action, with the valve 62 closed down, at position II the apparatus being set to work with slight auxiliary blower action, and at position III with powerful auxiliary blower 75

action. With open valve 62 the same applies to positions I and III as with closed valve 62, whereas in position II the apparatus is turned on but without any auxiliary blower action.

5 What I claim is:

1. In draft regulators for locomotives and the like, a steam auxiliary blower, a main steam valve, a steam control valve having steam outlet ports, an auxiliary blower valve having a 10 channel adapted to be connected with one of said outlets for the passage of a small quantity of steam, a connection between said channel and the auxiliary blower, means controlled by the main valve for maintaining said channel in open condition when the main valve is in closed position and acting upon opening of the main valve to adjust said blower valve to close said channel, said blower valve having a second channel adapted 15 to be connected with another outlet of the control valve for the passage of a larger quantity of steam to said connection independently of the main valve, said steam control valve includ-

ing means for controlling the flow of steam to each of said channels.

2. In draft regulators as claimed in claim 1 characterized by the provision of a fire box and a fire door therefor, and means connecting the fire door with the steam control valve whereby upon opening the fire door, said steam control valve is automatically adjusted to permit the passage of steam to the first mentioned channel while maintaining communication to the second 10 mentioned channel closed, said steam control valve being manually operable to a second position to open communication for passage of steam to the second mentioned channel.

3. In draft regulators as claimed in claim 1, 15 characterized by the provision of a fire box and a fire door therefor, an overgrate air admission flap in said fire door, means controlled by the steam control valve to effect the opening of said flap, and manually operable means to actuate the 20 steam control valve to actuate the flap opening means when said fire door is in closed position.

OSWALD HUWYLER.
